UNITED STATES PATENT OFFICE.

NICHOLAS GREIN, OF MILWAUKEE, WISCONSIN.

WOODWORKING-MACHINE.

1,100,130.

Specification of Letters Patent. Patented June 16, 1914.

Application filed August 28, 1913. Serial No. 787,052.

To all whom it may concern:

Be it known that I, NICHOLAS GREIN, a citizen of the United States, residing at Milwaukee, in the county of Milwaukee and 5 State of Wisconsin, have invented a certain new and useful Improvement in Woodworking-Machines, of which the following is a specification.

This invention relates to improvements in 10 the construction of machines for producing bodies having either an elliptical cross section or a similarly formed recess therein, and is especially applicable to that class of devices known as universal wood-working 15 machines.

An object of the invention is to provide a 20 machine for producing bodies having either an elliptical cross-section or a similarly formed recess therein, which is simple in construction and efficient in operation.

One of the more specific objects of the invention is to provide a mechanism for causing a forming implement to move along the path defining a theoretically correct ellipse.

25 Another object is to provide means for permitting variation in the form and size of the elliptical path described by the forming implement of the mechanism.

Still another object is to provide simple 30 and effective means for actuating and for permitting adjustment of the position of the forming implement.

A further object is to provide a device 35 which will produce either bodies of revolution having an elliptical cross-section, or elongated cylindrical or conical bodies having similar cross-sections.

Another object is to provide a device which 40 may be readily adjusted and manipulated to effectively form the various bodies to be constructed.

A clear conception of an embodiment of the invention may be had by referring to the drawings accompanying and forming a part 45 of this specification, in which like reference characters designate the same or similar parts in the various views.

Figure 1 is a transverse vertical section 50 through a wood-working machine showing a fragment of a body being formed. Fig. 2 is a fragmentary rear end elevation of a wood-working machine, the view being taken in the direction of the arrow A in Fig. 1. Fig. 3 is a fragmentary front end elevation of a 55 wood-working machine, the view being taken in the direction of the arrow B in

Fig. 1. Fig. 4 is a fragmentary transverse horizontal section through some of the elements of a wood-working machine, showing the relative positions of the supporting elements in dot and dash lines, the section being taken along the irregular line IV-IV of Fig. 1, looking in the direction of the arrow. Fig. 5 is a slightly enlarged diagram showing one form of elliptical path which the forming implement may be caused to travel. Fig. 6 is a similar diagram showing another form of elliptical path which the forming implement may be caused to travel. Fig. 7 is a similar diagram showing another 60 form of elliptical path which the forming implement may be caused to travel. 65

The device as disclosed herein is especially adapted for forming bodies of wood, but it is not desired to limit the invention to such 70 application.

The invention is applicable wherever it is desired to form a body having a semi-elliptical or semi-circular cross-section. As disclosed, the machine is especially applicable 75 in the art of pattern making, in which it is often desirable to form half-patterns having an elliptical or circular cross-section, and in which it may also be desirable to form core-boxes having recesses of semi-elliptical or 80 semi-circular cross-section therein.

The terms horizontal, vertical, front, rear and other terms of a similar nature, as used in this specification are merely used to facilitate definition of the invention and it is not 85 intended to limit the disposition of the elements to that disclosed.

The supporting column 1 is fixed at its lower end to any suitable either stationary or movable means, not shown. The cross 90 shaft 3 is vertically and angularly adjustably secured to the column 1 by means of the cross shaft supporting bracket 4 which may be moved both along and around the column 1 and clamped thereto in any desired position. The frame supporting bracket 55 is laterally and angularly adjustably secured to the cross shaft 3 by means of frame bracket clamps 5 and is provided with a side clamping portion in which the normally 95 vertically disposed frame bearing 6 is secured by means of the frame clamps 56.

The supporting frame consists essentially of a bearing 6 having two parallel frame guides 2 formed integral therewith. The 100 cross head bracket 28 is formed preferably 105 integral with the guides 2 of the frame and

has a transverse cross head guide slot 29 formed therein. The cross head block 30 snugly fits the slot 29 and has a central bore which forms a bearing for the pivot of the cross head bracket 44.

The upper and lower vertically slidable guide shaft brackets 8, 9 respectively, are formed with slides which closely fit the frame guides 2, and are rigidly connected to each other by means of the vertical guide shaft 7 which coacts with the bearing 6. The upper horizontal shaft 10 has a bearing in the upper bracket 8, and has a forwardly projecting end to which the bevel gear 31 and upper lever bracket 12 are rigidly secured. The lower horizontal shaft 11 has a bearing in the lower bracket 9, and has projecting ends to the forward of which the bevel gear 33 and lower lever bracket 13 are rigidly secured, and to the rearward of which the worm-wheel 40 and rear lower lever bracket 14 are rigidly secured. The gear shaft 16 is vertically supported in bearings formed in the brackets 8, 9 and has beveled gears 32, 34 fixed to its respective upper and lower ends, which mesh with the bevel gears 31, 33 respectively. The lower bracket 9 forms bearings for the worm shaft 54, intermediate which bearings the worm 39 which meshes with the worm-wheel 40 is fixed to the shaft 54. The actuating means, which for the purpose of simplifying the disclosure, is shown as a hand-wheel 45 but which may be of any other desirable form, is connected with an overhanging end of the shaft 54.

The rear lower lever bracket 14 forms bearings for the vertical screw-threaded lever shaft 20. The adjusting hand-wheel 42 serves as a means for permitting rotation of the shaft 20, the shaft 20 and hand-wheel 42 being normally locked in position by means of the lock nut 43. The cross head bracket 44 is mounted upon the screw-threaded lever shaft 20 and is adjustable along the shaft 20 by means of the hand-wheel 42.

The upper lever bracket 12 has the end portions of the screw-threaded upper lever shaft 18 fixed thereto. The bevel gear 46 has a screw-threaded central bore which coacts with the screw-threaded shaft 18 so that as the gear 46 is rotated it moves along the shaft 18. The upper adjusting bracket 50 has guiding portions which embrace the shaft 20 and which coact with the end surfaces of the hub of the gear 46. The upper adjusting shaft 52 is rotatably mounted in a bearing formed in the bracket 50 and has projecting ends to the one of which the bevel gear 47 which meshes with the bevel gear 46 is secured, and to the other of which the bevel gear 49 is fixed.

The lower lever bracket 13 has the end portions of the screw-threaded lower lever shaft 19 fixed thereto. The bevel gear 36

has a screw-threaded central bore which coacts with the screw-threaded shaft 19 so that as the gear 36 is rotated it moves along the shaft 19. The lower adjusting bracket 51 has guiding portions which embrace the shaft 19 and which coact with the end surfaces of the hub of the gear 36. The lower adjusting shaft 53 is rotatably mounted in a bearing formed in the bracket 51 and has projecting ends to the one of which the bevel gear 35 which meshes with the bevel gear 36, is secured, and to the other of which the bevel gear 37 is fixed.

The adjusting brackets 50, 51 are suitably guided in their respective lever brackets 12, 13 and have parallel projections which form supporting bearings for the implement carrier arm 15. The carrier arm 15 has bearings for the vertical adjusting shaft 17, formed thereon. The adjusting shaft 17 is rotatable by means of a hand-wheel 41 and has bevel gears 48, 38 which mesh with the bevel gears 49, 37 respectively, secured thereto.

To the lower extremity of the implement carrier arm 15, a direct driven forming implement or cutter 21 is adjustably secured. As disclosed, the cutter 21 is adapted for rotation about its axis by means of a direct-connected electric motor 24, although various devices for actuating the cutter 21 may be employed without departing from the scope of the present invention. The motor 24 and cutter 21 are angularly adjustable relative to the carrier arm 15 by means of the implement positioning clamp 27. The cutter 21 is located directly above and in close proximity to the body 22 which is to be formed. The body 22 is supported upon a supporting carriage comprising a rotatable means or table 23 carried by the laterally movable means or table 25 and adapted to be locked thereto. The table 25 is laterally movable along the tracks 26 and is adapted to be stationarily fixed upon the tracks.

During the normal operation of the device, the body to be formed is placed upon the supporting table, and, depending upon the character of the shape desired is either slowly rotated upon the table 23 or fed slowly along the tracks 26. The implement or cutter 21 after having been properly positioned is rotated at a very high rate of speed by means of its driving motor 24. The cutter 21 is then brought in contact with the body 22 by manipulating the various adjusting devices of the machine, and is caused to move along an elliptical or circular path by rotating the operating means or hand-wheel 45. Rotation of the hand-wheel 45 causes the shaft 54 and worm 39 to rotate, the rotation of which elements is transmitted through the worm-wheel 40 to the lower horizontal shaft 11. As the shaft 11 rotates, it swings the lower lever brackets 13, 14 about

70

95

100

105

110

115

120

125

130

the axis of the shaft 11 as a center. The swinging of the bracket 14 and the elements carried thereby, causes the cross-head block 30 to move along the slot 29 of the temporally 5 stationarily held bracket 28, thus causing the brackets 8, 9, vertical guide shaft 7 connecting the same and the elements carried thereby, to move vertically along the guides 2 and bearings 6. The extent of this 10 vertical movement will depend upon the distance between the axes of the shaft 11 and cross-head pivot bracket 44.

Simultaneously with the vertical movement of the brackets 8, 9 and of the elements 15 carried thereby, the lower lever bracket 13 is swung through an arc and the upper lever bracket 12 is caused to swing through a similar arc by means of the vertical gear shaft 16, the shaft 10 and the bevel gears 20 33, 34, 32, 31 which positively drivingly connect the brackets 13, 12. As the effective lengths of the levers formed by the brackets 13, 12 are preferably equal to each other, the elements connecting and carried by the 25 swinging ends of these levers will take parallel positions during the movement of the levers. The axis of the cutter 21 which is one of the elements carried by the levers, will therefore assume parallel positions independent of its angularity relative to the supporting means.

By referring to the diagram of Fig. 5, it will be noted that as the brackets 8, 9 and the elements carried thereby are moved vertically 35 at a definite rate of speed by means of the cross-head block 30, and as the cutter 21 is simultaneously moved through the arc of a circle about the axis of the vertically moving shaft 11 as a center, a theoretically 40 true ellipse is described by the cutter 21. The transverse or principal axis of the ellipse thus described is equal to double the distance marked X which distance corresponds to the distance between the axes of 45 the shafts 11 and 53. The conjugate or minor axis of the ellipse is equal to double the difference between the distances X and Y, the latter of which corresponds to the distance between the axes of the shaft 11 and 50 cross-head bracket 44. The movement of the cutter 21 may be continued to cause the cutter to traverse the entire ellipse or only a partial ellipse as desired.

The diagram of Fig. 6 represents a form 55 of ellipse produced by shortening the effective lengths of the lever shafts 19, 18 by amounts Z. This adjustment of the device is made by rotating the adjusting hand-wheel 41 thus causing the adjusting shaft 60 17, gears 38, 37, 48, 49, shafts 53, 52 and gears 35, 36, 47, 46 to rotate. The rotation of the gears 36, 46 causes them to move along their respective screw-threaded shafts 19, 18 and to alter the distances between 65 the axes of the shafts 53, 52 and the

shafts 11, 10 respectively, by carrying their respective brackets 51, 50 with the elements supported thereby to positions corresponding to the new positions assumed by the gears 36, 46. The positive gear and 70 shaft connection between the gears 36, 46 causes these gears during adjustment thereof to move equal amounts along their respective shafts and insures retention of equal throws of the upper and lower levers.

The diagram of Fig. 7 represents one form of ellipse produced by varying the effective lengths of the rear lever shaft 20, by an amount U. This adjustment of the device may be made by loosening the lock nut 43 and rotating the shaft 20 by means of the hand-wheel 42. Rotation of the shaft 20 causes the same due to its screw-threaded coaction, to move within the cross head bracket 44 and to shift the rear lower lever and the elements connected thereto, vertically. If the rotation of the shaft 20 is continued until the axis of the shaft 11 coincides with the axis of the cross-head pin, the path described by the cutter 21 will be a circle having a radius equal to the distance between the axes of the shafts 11 and 53. If the axis of the shaft 53 is brought in line with the axis of the cross-head pin, the path described by the cutter 21 will be a straight line parallel to the center line of the slot 29.

It will thus be noted that with the various adjustments provided for the upper and lower levers, the cutter 21 may be caused to move along an elliptical path of any desired form. If the pivots of these levers are below their swinging ends, the elliptical path described by the cutter 21 will be above the transverse axis of the ellipse, while if the lever pivots are above the swinging lever ends, the elliptical path described by the cutter 21 will be below the transverse axis of the ellipse.

If it is desired to form either a body of revolution having a semi-elliptical or semi-circular cross-section, or a similarly formed recess in a body, the body 22 is placed upon the table 23 and rotated about a fixed axis simultaneously with the movement of the cutter 21 along the desired elliptical or circular path. If it is desired to form either an elongated semi-cylindrical body having a semi-elliptical or semi-circular cross-section, or a similarly formed elongated recess in a body, the body 22 is placed upon the tables 23, 25 and moved laterally along the tracks 26 simultaneously with the movement of the cutter 21 along the desired elliptical or circular path.

The combined elements supported from the column 1 may be adjusted vertically along the column 1 or angularly about the column axis as a center, by releasing the clamp of the supporting bracket 4 and shifting the bracket 4 to the desired position.

The combined elements supported from the cross-shaft 3 may be adjusted horizontally along the shaft 3 or angularly about the shaft axis as a center, by releasing the clamps 5 of the frame bracket 55 and shifting the bracket 55 to the desired position. The frame of the machine and the elements supported thereby may be shifted angularly about the axis of the bearing 6 as a center, 10 by loosening the clamps 56 of the bracket 55 and shifting the frame to the desired position. As above noted, the angularity of the axis of the cutter 21 relative to the supporting table is also variable by means of the 15 clamp 27. Any of these various adjustments may be made simultaneously with the normal operation of the cutter 21, thus permitting construction of a great variety of differently formed bodies.

20 In order to insure ready actuation of the device, it would be necessary in the actual construction of the machine to provide suitable means, preferably in the form of weights, for balancing the various overhung 25 swinging elements, but such means has been omitted from the present disclosure in order to avoid undesirable complication thereof. Various devices for facilitating the various 30 adjustments of the machine in order to permit actuation thereof by a single operator, might also be incorporated in the device without departing from the scope of the present invention. The disclosure as made herein is intentionally made in its simplest 35 form in order to convey a clear understanding of the construction and principle of the device. It should be generally understood that it is not intended to be limited to the exact details herein shown and described except as set forth in the claims for obvious 40 modifications will occur to a person skilled in the art.

It is claimed and desired to secure by Letters Patent,—

45 1. In combination, an element swingable about an axis, means for simultaneously swinging said element about said axis and for producing harmonic motion of a point on said element, a forming implement movable in a curved path by said element, means for supporting a body to be formed, and means for permitting relative transverse movement of said supporting means and said implement.

50 2. In combination, an element swingable about an axis, means for simultaneously swinging said element about said axis and for producing harmonic motion of a point on said element, means for varying the limits of said harmonic motion, a forming implement movable in a curved path by said element, means for supporting a body to be formed, and means for permitting relative 55 transverse movement of said supporting means and said implement.

60 3. In combination, an element swingable about an axis, means for simultaneously swinging said element about said axis and for producing harmonic motion of a point on said element, a second element swingable about an axis, a member connecting said elements, a forming implement movable by said member, means for supporting a body to be formed, and means for permitting relative transverse movement of said supporting 65 means and said implement.

4. In combination, an element swingable about an axis, means for simultaneously swinging said element about said axis and for producing harmonic motion of a point on said element, means for varying the limits of said harmonic motion, a second element swingable about an axis, a member connecting said elements, a forming implement movable by said member, means for supporting a body to be formed, and means for permitting relative transverse movement of said supporting 75 means and said implement.

5. In combination, an element swingable about an axis, means for simultaneously swinging said element about said axis and for moving said axis laterally, a forming implement movable in an elliptical path by the movement of said element, means for supporting a body to be formed, and means for permitting relative transverse movement of said supporting 80 means and said implement.

6. In combination, an element swingable about an axis, means for simultaneously swinging said element about said axis and for moving said axis laterally, a forming implement movable in an elliptical path by the movement of said element, means for supporting a body to be formed, and means for permitting relative transverse movement of said supporting 85 means and said implement.

7. In combination, an element swingable about an axis, means for simultaneously swinging said element about said axis and for moving said axis laterally, a forming implement connected to a swinging point on said element and movable in an elliptical path by the movement of said element, means for varying the distance between said point of connection and said axis, means for supporting a body to be formed, and means for permitting relative transverse movement of said supporting 90 means and said implement.

8. In combination, an element swingable about an axis, means for simultaneously swinging said element about said axis and for moving said axis laterally, means for varying the limits of lateral movement of said axis, a forming implement connected to a swinging point on said element and movable in an elliptical path by the movement of said element, means for varying the 95

100

105

110

115

120

125

130

distance between said point of connection and said axis, means for supporting a body to be formed, and means for permitting relative transverse movement of said supporting means and said implement.

5 9. In combination, an element swingable about an axis, means for simultaneously swinging said element about said axis and for moving said axis laterally, a second element swingable about an axis, a member connecting said elements, a forming implement movable by said member, means for supporting a body to be formed, and means for permitting relative transverse movement 10 of said supporting means and said implement.

10 10. In combination, a plurality of elements swingable about a common axis, means for simultaneously swinging said elements about said axis, means coacting with one of said elements for producing harmonic motion of corresponding points on said elements, a forming implement movable in a curved path by another of said elements, 20 means for supporting a body to be formed, and means for permitting relative transverse movement of said supporting means and said implement.

15 11. In combination, a plurality of elements each swingable about an axis, means for simultaneously swinging said elements about their axes, means coacting with one of said elements for producing harmonic motion of points on said elements, a forming implement movable in a curved path by another of said elements, means for supporting a body to be formed, and means for permitting relative transverse movement of said supporting means and said implement.

20 12. In combination, a plurality of elements swingable about a common axis, means for simultaneously swinging said elements about said axis, means coacting with one of said elements for moving said axis laterally, a forming implement movable by another of said elements, means for supporting a body to be formed, and means for permitting relative transverse movement of said supporting means and said implement.

25 13. In combination, a plurality of elements each swingable about an axis, means for simultaneously swinging said elements about their axes, means coacting with one of said elements for moving said axes laterally, a forming implement movable by another of said elements, means for supporting a body to be formed, and means for permitting relative transverse movement of said supporting means and said implement.

30 14. In combination, a pair of elements swingable about a common axis, means for simultaneously swinging said elements about said axis, means coacting with one of said elements for producing harmonic motion of points on said elements, a third element

swingable about an independent axis, a member connecting said third element with the other of said pair of elements, a forming implement carried by said member and movable in an elliptical path by the movement 70 of said elements, means for supporting a body to be formed, and means for permitting relative transverse movement of said supporting means and said implement.

15 15. In combination, a pair of elements swingable about a common axis, means for simultaneously swinging said elements about said axis, means coacting with one of said elements for moving said axis laterally, a third element swingable about an independent axis, a member connecting said third element with the other of said pair of elements, a forming implement carried by said member and movable by the movement of said element, means for supporting a body to be formed, and means for permitting relative transverse movement of said supporting means and said implement.

20 16. In combination, a frame, a bracket movable in said frame, a lever pivoted in said bracket, means for simultaneously swinging said lever about its pivot and for producing rectilineal movement of a point on said lever, a forming implement connected to said lever and movable in an elliptical path by the movement of said lever, means for supporting a body to be formed, and means for permitting relative transverse movement of said supporting means and said implement.

25 17. In combination, a frame, a bracket movable in said frame, a lever pivoted in said bracket, means for simultaneously swinging said lever about its pivot and for moving said bracket to produce harmonic motion of a point on said lever, a forming implement connected to said lever and movable in a curved path by the movement of said lever, means for supporting a body to be formed, and means for permitting relative transverse movement of said supporting means and said implement.

30 18. In combination, a frame, a bracket movable in said frame, a lever pivoted in said bracket, means for simultaneously swinging said lever about its pivot and for moving said bracket along said frame, a forming implement connected to said lever and movable in an elliptical path by the movement of said lever, means for supporting a body to be formed, and means for permitting relative transverse movement of said supporting means and said implement.

35 19. In combination, a frame, a bracket movable in said frame, a lever pivoted in said bracket, means for simultaneously swinging said lever about its pivot and for producing rectilineal movement of a point on said lever, means for varying the limits of said rectilineal movement of said point,

- a forming implement connected to said lever and movable in an elliptical path by the movement of said lever, means for supporting a body to be formed, and means for permitting relative transverse movement of said supporting means and said implement. 65

5 20. In combination, a frame, a bracket movable in said frame, a lever pivoted in said bracket, means for simultaneously swinging said lever about its pivot and for moving said bracket to produce harmonic motion of a point on said lever, means for varying the limits of said harmonic motion, a forming implement connected to said lever and movable in a curved path by the movement of said lever, means for supporting a body to be formed, and means for permitting relative transverse movement of said supporting means and said implement. 70

29. In combination, a frame, a bracket movable in said frame, a pair of levers pivoted in said bracket, means for simultaneously swinging said levers about their pivots, a crosshead pivotally connected to one of said levers and movable in said frame in a direction transverse relative to the direction of movement of said bracket, a forming implement movable by the other of said levers, and means for moving a body to be formed toward said forming implement. 140

100 105 110 115 120 125 130 135 140

30. In combination, an element swingable about an axis, means for simultaneously swinging said element about said axis and for producing harmonic motion of a point 5 on said element, a forming implement movable in a curved path by said element, means for supporting a body to be formed, and means for permitting relative transverse movement of the portion of the body being 10 formed and of said implement.

31. In combination, an element swingable about an axis, means for simultaneously swinging said element about said axis and for moving said axis laterally, a forming 15 implement movable in an elliptical path by the movement of said element, means for supporting a body to be formed, and means for permitting relative transverse movement of the portion of the body being 20 formed and of said implement.

32. In combination, an element swingable about an axis, means for simultaneously swinging said element about said axis and for producing harmonic motion of a point 25 on said element, a forming implement,

means for supporting a body to be formed, said implement and said supporting means being relatively movable in a curved path by the movement of said element, and means for permitting relative transverse movement 30 of the portion of the body being formed and of said implement.

33. In combination, an element swingable about an axis, means for simultaneously swinging said element about said axis and 35 for moving said axis laterally, a forming implement, means for supporting a body to be formed, said implement and said supporting means being relatively movable in a curved path by the movement of said element, and means for permitting relative 40 transverse movement of the portion of the body being formed and of said implement.

In testimony whereof, the signature of the inventor is affixed hereto in the presence of 45 two witnesses.

NICHOLAS GREIN.

Witnesses:

HERMAN SCHUERMAN,
OSCAR C. MEHL.
